UNITED STATES PATENT OFFICE.

EDMOND G. DU MAZUEL, OF NEW YORK, N. Y.

MEANS FOR REINFORCING CONCRETE.

No. 876,471.

Specification of Letters Patent.

Patented Jan. 14, 1908

Application filed February 19, 1907. Serial No. 358,261.

To all whom it may concern:

Be it known that I, EDMOND G. DU MAZUEL, a consulting engineer, a citizen of the United States, residing at New York city, in the county of New York and State of New York, have invented an Improved Means for Reinforcing Concrete, of which the following is a specification.

My invention relates to metal members to be used as sheet piles, or as a reinforcement for concrete and the like, to give the required area of metal to reinforce concrete slabs, beams, columns and other forms of concrete requiring reinforcement, and to give a maximum strength for a minimum area of such reinforcement.

It has for its object a metal member so shaped as to utilize all of the section of metal employed, and arranged so as to afford the necessary cross-sectional area of metal for a given cross-sectional area of concrete; and to increase to the maximum the strength of said cross-section without necessitating the use of form work or special additional members such as spacing wires, rods, etc., also, to provide a construction for uniting or locking a number of such members in a ready and water-tight manner.

These objects are attained by means of the construction illustrated in the accompanying drawings in which—

Figure 1 is a general cross-sectional view of a slab of concrete for floors, roofs or walls provided with my improved reinforcing members. Fig. 2 is a diagrammatic view illustrating the cross-sectional form of my improved reinforcing member. Fig. 3 is a perspective view of the improved reinforcing member. Fig. 4 is a perspective view showing a method of securing the reinforcing member to a beam, girder, column or upright. Fig. 5 is a perspective view showing two reinforcing members joined together, locking and overlapping each other.

Similar characters of reference designate corresponding parts throughout the several views.

Referring to the drawings it will be seen that my improved reinforcing member M consists of a corrugated sheet of metal of gage G, Fig. 2, previously determined by formula, and in cross-section a series of reversed or substantially S-shaped curves, the spaces between successive S-shaped elements being contracted intermediate of the top and bottoms of said corrugations. As shown

in Fig. 2, the S-shaped curves are formed by arcs struck from the centers C and are tangent to one another. To insure a contraction it is necessary for the pitch two S, of the corrugations, to be less than twice the depth d of the same. This member M consists of a series or number of such curves or corrugations of any desired width and length; and may, in the sheet form shown in Fig. 3 or in other suitable forms, be vertically driven into the ground as piles or sheet piles.

When floors, roofs, ceilings, flat or other arches are formed or composed of concrete, and the same is to be reinforced with my improved reinforcing members, these may then be placed from girder to girder, beam to beam, or from springing to springing of said floors, roofs, flat or other arches, and on top and bottom of the girders, beams or springings, as shown in Fig. 4, and the concrete or the like filled in in the usual manner, without necessitating the use of forms.

The members M may be secured to beams uprights I and the like, Fig. 4, by the use of a sharp V-shaped chisel, which, when driven in at the corners or sides of flanges and the like against abutting grooves, will form a tongue or spur K over said corners or sides, thereby locking the same. If stronger locking is desired, wire can be passed through the openings O thus formed and around the supports I, thereby obtaining a stronger and firmer hold. When more than one member is required, they can be joined together at the ends and sides by springing one onto the other, the ends of the members or their full side sets of reversed curves, as shown at J Figs. 1 and 5, thus making perfect watertight joints. These members may also be securely locked together, reference being had to Fig. 5, by the use of a V-shaped chisel which, when driven against the lower side of the members M, will cut out or form V-shaped tongues or spurs K that will bend over and secure the said members to one another. When used for columns, caissons, piers, intakes, penstocks, and the like, the members, may in springing one or more around a required form or shape, also be joined in the same manner as above described, the concrete being applied or troweled on inside and outside. When used as sheet piles, or piles, the members can be driven into the desired places and joined together in the manner already described. The member M is corrugated and provides between

105
110

successive corrugations a contraction intermediate of the top and bottom and of such proportion that one member may be readily sprung one onto the other. The construction, further, insures the concrete filling being securely held, and does away with the use of forms in applying same.

As shown in Fig. 1, the member M is embedded in concrete A and B of depth H, whose neutral axis N—N is determined in the usual manner by general formulæ. The depth d of the curves or corrugations should be assumed so as not to reach the neutral axis N—N and so as to allow complete embedding in the concrete, and is equal to the distance between the upper and lower tangents to the curves, that are parallel to its horizontal axis X—X. The pitch S of the curves or distance between the vertical center lines on which are the centers C, C, determines the degree of reversal of the curves. This pitch S is one-half of the pitch of said corrugations, which latter pitch must be smaller than twice the depth d of the curves or corrugations, being preferably eleven-eighths of the same to provide the most suitable contraction. The distance S also determines the resistance and opposing forces along lines C—C at intersections of line X—X in and by the reinforcing member M, originated by the series or multitude of small and adjacent concrete beams formed by the concrete A and B, Fig. 1, in the adjacent channels, which are formed by the corrugations, when these series of theoretical, small concrete beams act one against the other while a portion or the entire section of the reinforced concrete is subjected to a stress. The depth d and pitch S of the curves being fixed as above described, the radii R of the continuous S-shaped reversed curves will be equal to one-quarter of the ratio of the sum of the squares of the depth d and pitch S, to the depth d; the centers C, O of the curves being located on the vertical center lines which determine the pitch. Although the corrugations have been shown in cross-section composed of portions of circles tangent to one another, yet an approximate and similar construction is possible in which the cross-section of the corrugations are partial circles not tangent to one another, but portions of circles united by a short line tangent thereto.

The construction of my improved corrugated member possesses numerous advantages over the prior art such as, for example, affording full value of all the metal, in that the distribution of the same is uniform or symmetrical; eliminating all form work, and thereby reducing cost and skilled labor; and enabling all joints to be readily sprung, the

same being water-tight, and not requiring skilled labor.

Claim:

1. A corrugated metal reinforcing member in cross section a series of reversed or substantially S-shaped curves, the corrugations of which form spaces contracted intermediate of the tops and bottoms of the corrugations.

2. Reinforcing members for concrete structures and the like consisting of corrugated metal reinforcing members in cross section a series of reversed or substantially S-shaped curves, the corrugations of which form spaces contracted intermediate of the tops and bottoms of the corrugations.

3. A corrugated metal reinforcing member, in cross section a series of reversed or substantially S-shaped curves, the pitch of the corrugations being substantially less than twice their depth.

4. A corrugated metal member, in cross section a series of reversed or substantially S-shaped curves the ratio of the pitch of the corrugations to the depth of same being eleven-eighths.

5. A structure comprising a series of corrugated metal reinforcing members in cross section a series of reversed or substantially S-shaped curves, the corrugations of which form spaces contracted intermediate of the tops and bottoms of the corrugations; whereby the members are sprung the one onto the next preceding and succeeding member to form a continuous and water-tight series of members.

6. The combination with a support, of a corrugated metal reinforcing member in cross section a series of reversed or substantially S-shaped curves, the corrugations of which form spaces contracted intermediate of the tops and bottoms of the corrugations; and means to secure said member to said support.

7. A structure comprising a series of corrugated metal reinforcing members in cross section a series of reversed or substantially S-shaped curves, the corrugations of which form spaces contracted intermediate of the tops and bottoms of the corrugations, whereby the members are sprung one onto the next preceding and succeeding member to form a continuous and water-tight series of members, and securing spurs cut from same and integral therewith.

In testimony whereof, I have signed my name to this specification, in the presence of two subscribing witnesses.

E. G. DU MAZUEL.
